RETARDED SELF-CLOSING FAUCET

James F. Molloy, Oakland, Calif.

Application October 8, 1941, Serial No. 414,103

2 Claims. (Cl. 251—138)

This invention relates to improvements in retarded self-closing faucets and more particularly to the retarding means.

Among the objects of the invention is the simplification of the combination and arrangement of the elements for opening and retarding the closing of the valve controlling the flow through the faucet.

Another object is to combine the working elements in a compact unit for easy replacement in existing faucets in this class.

Another object is to minimize wear in the working parts to maintain accuracy in the timing interval, throughout the life of the assembly.

Another object is to reduce the necessary spring tension interposed in the opening moment.

A further object is the disposal of external seepage through the packing means.

Other objects and advantages will appear as the description progresses.

In this specification and the accompanying drawing the invention is disclosed in its preferred form. But it is to be understood that it is not limited to this form, because it may be embodied in modifications within the spirit of the invention as defined in the claims following the description.

It has been common practice in this art to use cuppleathers and other forms of yielding packing, in the retarding means; also to close the valve by spring tension. Such packings are subject to deterioration in continued use, resulting in progressive shortening of the retarding period in closing. Spring closed valves are subject to leakage and water hammer in high pressure water districts, and the parts are not easily accessible for repair or replacement in those valves in the art known to me.

Broadly stated the present invention consists in providing a compactly assembled interchangeable unit combining all the working parts necessary, that may be easily and quickly removed and replaced in the body of the faucet; and in which the valve is positively closed by the service pressure and the retarding elements are not in direct wearing contact with each other.

The single figure of the drawing shows:

A vertical section of a water faucet constructed in accordance with this invention.

In detail the construction illustrated in the drawing comprises the conventional body portion 1 having the threaded inlet pipe 2 adapted to be coupled to the water or other fluid service pipe and having the running nut 3 for attaching the faucet to the basin or other fixture.

The body has the annular internal flange 4

5 and the central enlarged portion 5 below the neck 6, that is externally threaded to receive the internally threaded coupling nut 7. The discharge spout 8 leads from the chamber formed by the enlarged portion at 5. The top and the internal bore of the neck 6, the top surface of the flange 4 and the center opening therein are accurately machined. The compressible packing washer 9 is interposed between the coupling nut and the top of the neck 6.

The annular cap 10 is closed at the top 11 and has the external flange 10' with radial notches in its lower surface and beneath the top flange of the nut 7. The pressure handle 12 preferably telescopes over the cap 10 and is slidably joined thereto by the thrust screw 13 having its head countersunk in the under side of the top 11.

The cylindrical valve block 14 has a reduced lower end snugly bearing against the flange 4 and filling the center opening therein. It has the lower inlet valve opening 15 surrounded by a raised bead forming the inlet valveseat. The diameter of the block 14 is a snug sliding fit within the bore of the neck 6, and terminates below the top thereof, and has an upstanding annular flange 16.

The gland neck 17 has the enlarged base 18 resting upon the flange 16 with which it makes a substantially pressure tight fit. This base engages under the flange 10' on the cap 10 and is depressed by the coupling nut 7 screwed onto the neck 6 of the body. The neck of the gland 17 is externally threaded to receive the packing coupling nut 19 which compresses the soft packing 21. The body portion 5, block 14 and gland 17—18 form in effect a single unit having an internal bore.

The valve 22 is screwed onto the end of the valve stem 23 which extends upwardly through the assembly to the head of the thrust screw 13, and is sealed against leakage by the soft packing 21. The valve 22 has the composition insert 24, engaging the valveseat bead surrounding the opening 15, against which it is pressed by the service pressure through the inlet 2. The stem 23 is slidably guided in the gland 17, and is of less diameter than the inlet 15.

The valve block 14 is counterbored to receive the piston 25 slidable therein. The lower end of the piston forms a valve seat for the valve 26 resting on the disk 26' fixed on the stem 23, with an annular inlet passage surrounding the stem 23. The piston depressing cross pin 27 in the stem limits the opening of the valve at 26. The bottom of the block 14 has the lateral out-

lets such as 28, 29, preferably three or more, extending from the inlet 15 into the body of the faucet at 5. The longitudinal by-pass 30 is bored in the wall of the block 14 from its top into the lateral outlet 28. The spring 31, interposed between the cap 32 threaded on the upper end of the stem 23 and the nut 19, urges the handle 12 upward into the normal position; and also maintains the valve 22 closed should the water pressure fail.

This invention operates substantially as follows: With all parts in the positions shown in the drawing and the valve 22 closed by the service pressure in 2; depressing the handle 12 to the limit of the spring 31, acting through the thrust screw 13 and the stem 23, opens the valve at 22 to full capacity and causes the cross pin 27 to depress the piston 25. The inrush of water through the inlet 15 escapes through the lateral passages 28, 29 and through the spout 8. It also rises upwardly into the counterbore lifting the piston 25 against the pin 27. This opens the valve at 26 and fills the chamber 33 above the piston.

The retarding action is timed by the volume of water impounded in the chamber 33. The upward urge of the fluid pressure against the valve 22, lifts the piston 25, causing this impounded water to seep slowly past the periphery of the piston and the contiguous walls of the counterbore in the block 14. This interposes a dash-pot action for retarding the reclosing of the valve 22. The timed interval between the opening and closing of this valve is determined by the speed of this seepage. There is at all times a thin film of water between the periphery of the piston and the counterbore acting as a lubricant to prevent wear. Turning the cap 32 down on the upper end of the threaded stem 23 shortens the timing interval by increasing the tension of the spring 31. Turning the cap 32 up on the threaded stem lengthens the timing interval by decreasing the tension of the spring 31, urging the valve 22 upward.

In water districts where the water may contain alkaline or other corrosive impurities, it is advisable to make the piston 25 and block 14 of a suitable non-corrosive metal, or plastic, such as hard rubber compound or the like.

Any leakage past the soft packing 21, accumu-

lates in the cap 10 and flows downward through radial notches formed in the bottom of the flange 10' and is syphoned through the by-pass 30 by the aspirating effect of the water flowing through the lateral outlet 28.

Having thus described this invention what is claimed and desired to secure by Letters Patent is:

1. A faucet in the class described including a body having a service inlet and outlet; a cap forming a continuation of the upper portion of said body; a pressure handle above said cap and slidably attached thereto by a thrust means; a counterbored valve block interposed in said body between said inlet and outlet and having an inlet valve seat in its lower portion and an outlet opening into said body; a piston slidable in the counterbore in said block; a stem slidably guided in said block and extending through said piston and protruding at both ends of said block; a valve on said stem beneath said piston, and piston depressing means on said stem; a valve on said stem adapted to close said service inlet in said block; an adjustable spring cap on the opposite end of said stem; and a spring interposed between said spring cap and said block.
2. A faucet in the class described including a body having a service inlet and outlet; a cap forming a continuation of the upper portion of said body; a pressure handle above said cap and having a thrust member extending through the top of said cap; a counterbored valve block interposed in said body between said service inlet and outlet and having an inlet valve seat in its lower portion and an outlet into said body; a piston slidable in the counterbore in said block; a gland neck extending into said cap and having a base closing the top of said counterbore; a stem slidably guided in said gland neck and extending through said piston, block and gland neck; a valve on said stem beneath said piston, and piston depressing means on said stem; a valve on said stem adapted to close the inlet opening in said block; a spring cap on the end of said stem in operative relation to the thrust member on said pressure handle; and a spring interposed between said spring cap and said gland neck.

JAMES F. MOLLOY.
